(57) **CLAIM**

The ornamental design for a nail polisher, as shown and described.

DESCRIPTION

FIG. 1 is a front, right and top perspective view of a nail polisher, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is a perspective view thereof; and,

FIG. 10 is another perspective view thereof.

The broken lines in the drawings show portions of the nail polisher that form no part of the claimed design. Additional broken lines showing a circle and square base in FIGS. 9 and 10 show environment and form no part of the claimed design.
